United States Patent Office.

WILLIAM A. MIDDLETON AND JOHN A. HALLER, OF HARRISBURG, PENNSYLVANIA.

Letters Patent No. 80,870, dated August 11, 1868.

IMPROVED HORSE-HITCH.

The Schedule referred to in these Letters Patent and making part of the same.

TO ALL WHOM IT MAY CONCERN:

Be it known that we, WILLIAM A. MIDDLETON and JOHN A. HALLER, of Harrisburg, in the county of Dauphin, and State of Pennsylvania, have invented a new and useful Horse-Hitch; and we do hereby declare that the following is a full, clear, and exact description of the construction and operation of the same, reference being had to the annexed drawings, making a part of this specification, in which—

Figure 1 is a perspective view.

Figure 2 is a vertical section.

Figure 3 is a top view.

Figures 4 and 5 are sectional views.

We construct our horse-hitch in three parts, a frame, a holder, and a floor-piece.

The frame O O', W W', fig. 1, has a base, W W', in which are two screw-seats, T T', and a recess between them for the reception and retention of the floor, Z Z', as shown in fig. 3. The end edge of floor-recess is bevelled, to hold the floor down when the frame is screwed fast. On the base-ends, W W', fig. 1, are two walls, O O', which come to a rounded top above. In the top are cast two pieces, H H', which are parallel to each other, and at right angles to the walls, O O', and both are a little out of the transverse centre of the frame, thus leaving or forming a slot, K, between them. The piece H is embedded beneath the round top, and H' is flush on the top; thus said slot K is made to be oblique, or in the direction K W', fig. 2, said piece H' being higher in the frame than the piece H. An open mouth is thus formed, to enable the strap to be easily inserted. Said slot is made oblique, to shoot the inserted end of strap out clear toward W', so that it can be manipulated easily, to further insert it under the wing of the holder, as shown at X', fig. 2, and is made narrow or slender, so that the strap cannot be handled to loosen it when hitched, except in a proper manner. The entrances to the slot are rounded, to prevent cutting the strap.

The holder, fig. 5, has trunnions, L L', and a thumb-piece on one of them, which extends outside of the frame, as shown at R, fig. 3. The holder has two wings, α α' , fig. 5, equidistant from its axis. Said wings are distant enough, first, to strike the piece H, fig. 1, which serves as a stop when the strap is to be hitched shorter, thereby freeing the hitch on the floor, and letting the strap move freely in the direction of V' V, fig. 1; second, distant enough to catch and hitch the strap, when the strap is drawn in the direction V V', fig. 2, thereby revolving the holder, and causing one of said wings to impinge on the serrated floor, 1, 2, 3, &c., and holding the strap, as at X', fig. 2.

The floor Z Z' has a depressed part, 1, 2, 3, &c., which is serrated, and two raised, bevelled ends, z z', as shown in fig. 2. The body of the floor is nearly rectangular, having its corners rounded, as shown in fig. 4, and on its long sides are two trunnion-rests, n n', which fit into similarly-shaped cuts in the sides of the frame, as shown at n, fig. 1.

The operations, as already explained, may be here enumerated.

First. A rapid and sure hitch, as all the working parts are sheltered from the reach of an animal, and the ingress to the holder is easy and speedy, even in the dark.

Second. A forced hitch, as an animal can be drawn up and held in a moment.

Third. A variable hitch, as the strap can be drawn up to any desired length, without untying.

Our hitch can also be used as a line-holder; but whereas G. R. Nebinger, of Lewisberry, Pennsylvania, did obtain Letters Patent, which letters bear date, February 18, 1868, on a line-clamp, in which he employs some parts in some respects similar for said purpose; and whereas the said G. R. Nebinger did sell and assign the said patent for the said purpose to us, the present applicants for the above-described horse-hitch, we hereby disclaim the use of the said parts for the said purpose; but

What we do claim, and desire to secure by Letters Patent of the United States, is—

1. So forming the slot K in the top of the frame O O', as to serve the several purposes substantially in the manner as herein set forth.
2. The adjustable floor Z Z', provided with the trunnion-rests n n', and the serrated part 1, 2, 3, &c., in combination with the frame W W', substantially as herein set forth.
3. The holder S, when made with the equidistant wings a a', and the thumb-piece R, in combination with the frame O O', W W', and floor Z Z', for the purpose specified.

WM. A. MIDDLETON,
JNO. A. HALLER.
